(57) **CLAIM**

The ornamental design for a handle for power supply, as shown and described.

DESCRIPTION

FIG. 1 is a top, front, right side perspective view of a handle for power supply, showing our new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, left side perspective view of the handle for power supply of FIG. 1, shown at a reduced scale and in a condition of use; and,

FIG. 10 is a top, rear, left side perspective view thereof. The broken lines in the drawings depict portions of the handle for power supply that form no part of the claimed design. The broken lines showing a power supply in FIGS. 9 and 10 depict environmental subject matter that forms no part of the claimed design.

1 Claim, 10 Drawing Sheets
